UNITED STATES. PATENT OFFICE.

CHRISTIAN IVERSON, OF BOULDER CREEK, CALIFORNIA.

SWIMMING-GLOVE.

942,262.

Specification of Letters Patent.

Patented Dec. 7, 1909.

Application filed June 25, 1909. Serial No. 504,357.

To all whom it may concern:

Be it known that I, CHRISTIAN IVERSON, a citizen of the United States, residing at Boulder Creek, in the county of Santa Cruz and State of California, have invented certain new and useful Improvements in Swimming-Gloves, of which the following is a specification.

This invention relates to improvements in swimming gloves and consists in the novel features of construction hereinafter described and claimed.

The object of the invention is to provide a glove of this character having the usual finger stalls, with a back strap extending between the second finger stall and the wrist strap, whereby the glove will be effectively prevented from slipping off of the hand while in use, the construction being such that the glove may be produced at a smaller cost and is rendered more durable and efficient than similar devices heretofore used.

The above object is attained in the construction illustrated in the accompanying drawing, in which,

Figure 1 is a perspective view of one of my improved swimming gloves adapted for use on the right hand; and Fig. 2 is a central longitudinal sectional view.

The glove comprises a flexible sheet 1 having substantially the contour of the hand when the fingers are spread apart. It is preferably made of water-proof material such as fabric covered with rubber. Upon the rear face of the sheet are provided stalls 2, 3, 4, 5, 6 for the reception of the thumb and four fingers, said stalls being of suitable size and shape, and made preferably from fabric or similar flexible material, whereby the entire glove will give to the closing movement of the hand. It will be noted, that the portions of the sheet 1 between the stalls form webs, and in order to support these web portions when the hand is opened, the edge of the sheet is folded over upon itself in a rearward direction, as shown at 7, and secured by a row of stitching 8. This fold forms a reinforcing rim and is made to extend entirely around the sheet, as clearly seen in Fig. 1. The several stalls are similarly secured by stitching 9 and the outer ends of all of them are inserted beneath the fold 7 and closed by the same and by the stitching 8. The outer side edges of the

thumb stall 2 and the little finger stall 6 are also arranged and secured beneath the fold 7, as shown in Fig. 1.

In order to effectively retain the glove upon the hand, I provide a wrist band or strap 10 and a back strap 11, which latter is formed integral with the stall 4 for the second finger and has at its end a loop 12 for the reception of the wrist strap. Said wrist strap has its intermediate portion arranged transversely across the rear edge of the sheet 1 and secured thereto by one or more rows of stitching 13, and on the short end of said strap is secured a buckle 14 which permits it to be adjusted. The loop 12 loosely receives the long end of the wrist strap and is formed by folding the free end of the back strap upon itself and securing it by stitching 15. The back strap effectively prevents the fingers from slipping out of the stalls when the hand is closed and also when it is opened, and by making said back strap integral with the second finger stall 4, the glove is not only rendered stronger and more durable, but also less expensive and easier to make.

The use and operation of the invention is obvious from the foregoing, and it will be understood that the left hand glove is similar to but the reverse of the one illustrated.

What I claim is,

A swimming glove comprising a flexible sheet of water-proof material having its edge folded over and secured to form a reinforcing rim, an adjustable wrist strap secured across the inner edge of the sheet, a centrally arranged stall for the second finger secured to the rear face of the sheet and having its inner end extended to form an integral back strap, the latter having its extremity folded upon itself and secured to provide a loop for the wrist strap, stalls for the thumb and first finger arranged upon the sheet on one side of the second finger stall, and stalls for the third and fourth fingers arranged upon the sheet on the other side of the second finger stall.

In testimony whereof I affix my signature in presence of two witnesses.

CHRIS. IVERSON.
